LIPSTICK CASINGS

Aurelia M. Wahle, Boulogne-Billancourt, France, assignor to Ejectoret S.A., Geneva, Switzerland, a Swiss company

Filed Oct. 14, 1958, Ser. No. 767,162

4 Claims. (Cl. 206—56)

This invention relates to lipstick holders and more particularly to lipstick cases for receiving and discharging lipstick refills or cartridges.

It is one of the objects of the present invention to provide means improving facile removal of a lipstick refill from a lipstick casing, in which the refill housing is completely accommodated, hidden from view and is thus not immediately accessible, when the lipstick refill is to be replaced.

It is another object of the present invention to provide means affording easy insertion of a lipstick refill in a lipstick case and automatic ejection of the lipstick refill without causing any soiling of the hand or garment of the user.

It is another aim of the invention to provide means conducive to a simplified construction of the lipstick case or holder which requires only a few parts, may be readily manufactured through mass production methods at a greatly reduced cost, and is very efficacious in operation.

It is still a further object of the present invention to provide means ensuring easy ejection operation from the lipstick case without requiring any instructions for the user for disposing of used or replaceable refills or cartridges.

Yet a further object of the present invention is to provide means redounding to an esthetically pleasing construction of a lipstick case or holder for a refill or cartridge, which holder may be of similar outer appearance as other ordinary lipstick holders now on the market, but distinguishes from the same by the incorporation in the interior of the lipstick case of means for readily ejecting the refill or cartridge when replacement therefor is desired.

Still another object of the invention is to provide means readily applicable to a lipstick case of predetermined structure, so as to transform the same into an ejector-type lipstick case pursuant to this invention.

The above and other objects of the invention will become further apparent from the following detailed description, reference being made to the accompanying drawings, showing preferred embodiments of the invention.

In the drawings which illustrate the best modes presently contemplated of carrying out the invention:

Fig. 1 is a view in elevation and partly in section of a lipstick casing and cover containing a lipstick refill pursuant to the present invention;

Fig. 2 is a vertical sectional view through the casing and refill, the cover being removed;

Fig. 3 is a view similar to Fig. 1 with the cover removed and the refill partially ejected from the casing;

Fig. 4 is a vertical sectional view taken through the casing of a modified embodiment of the invention, the refill being shown in elevation, the casing cover being removed;

2

Fig. 5 is a bottom view of the embodiment shown in Fig. 4, as seen from the line 5—5 of Fig. 4;

Fig. 6 is a view similar to Fig. 4 and illustrates a further modified embodiment of the present invention, the casing cover being shown in broken line;

Fig. 7 is a view similar to Fig. 1 pursuant to an additional embodiment of the invention; and

Fig. 8 is a view similar to that of Fig. 3 showing the embodiment of Fig. 7 in a different position and with cover for the casing removed.

Referring now to Figs. 1-3 in detail, there is shown a housing 10 for a lipstick refill cartridge 12 provided with a lipstick 14, pursuant to the present invention. The housing 10 comprises a casing 16, in which the refill cartridge 12 is contained, and a cover 18 for closing the casing. The cover 18 is constituted by a cylindrical member, preferably formed of a suitable metal or other useful material, which has a closed end 20 and an open end defined by a marginal end rim 22.

The casing 16 is constituted by the telescopically related cylindrical sleeves 24 and 26 each formed preferably of a suitable metal, plastic or other material; the inner sleeve 24 being disposed within the outer sleeve 26. The inner sleeve is open at both ends thereof, its outer end being defined by an inturned peripheral flange 28 and its inner end being defined by a marginal end rim 30. Upwardly from its inner end 30, the inner sleeve is provided, on its outer surface, with an integral circumferential collar 32. Downwardly from its outer end 28, and upwardly from the collar 32, the inner sleeve is provided on its inner surface with an integral inwardly directed circumferential bulge 34, the function of which is hereinafter described.

The outer sleeve 26 is open at both its ends. Its lower or outer end is defined by a marginal end rim 36 provided at the free end of the sleeve portion 38 of enlarged diameter. The upper or inner end of the outer sleeve is defined by an integral outwardly directed circumferential bulge 40 provided adjacent the free end of the reduced diameter sleeve portion 42. The sleeve portions 38 and 42 are integral with each other and define an inwardly directed circumferential shoulder 44 therebetween. A sleeve 46 is secured to the inner surface of the enlarged sleeve portion 38 at the open end 36 of the latter, a compression spring 48 being seated between the upper end of sleeve 46 and collar 32 of the inner sleeve 24.

The lipstick refill cartridge 12 is of conventional construction and is well known in the art so that detailed description thereof is deemed to be unnecessary. As here shown, the refill cartridge comprises a cylindrical cup 50 in which the lipstick 14 is mounted. The cup is mounted for relative movement in an inner sleeve 52 having an open outer end 54 and provided at its closed inner end with the footpiece 56. A compression spring 58, seated within the footpiece 56, bears against the cup 50. Outer end 54 normally comes to abut against inner flange 28.

The inner sleeve 52 is mounted for relative movement within an outer sleeve 60 which has a lower marginal end 62 which abuts the footpiece 56 and an upper opening defined by an upper marginal end 64. It will be understood that the inner sleeve 52 is coupled in conventional fashion, as shown at 66, to the outer sleeve 60, and the cup 50 is coupled in conventional fashion to the inner sleeve 52, whereby relative rotation of the inner and outer sleeves 52 and 60 will result in movement of the cup 50 longitudinally of the inner sleeve for projecting the lipstick 14 through the opening defined by the circular flange 28 in the casing 24 or for retracting the

lipstick within the casing, depending upon the direction of relative rotation of the sleeves of the lipstick cartridge.

With the lipstick cartridge disposed within the casing, as best shown in Fig. 2, the flange 28 of the casing serves as a detent or abutment for the cartridge so as to properly position the latter within the casing. The bulge 34 of the inner casing sleeve 24 is in frictional engagement with the outer sleeve of the cartridge and the friction ring 46 in the outer casing sleeve 26 is in frictional engagement with the footpiece 56 provided on the inner sleeve 52 of the refill cartridge.

Consequently, if the operator holds the inner casing sleeve 24 and rotates the outer casing sleeve 26 relative thereto, the inner cartridge sleeve, which is frictionally coupled to the outer casing sleeve will rotate relative to the outer cartridge sleeve which is frictionally coupled to the inner casing sleeve, whereby to effect the described movement of the lipstick 14 for projection from, or retraction into the casing. The spring 58 tends to facilitate the projection of the lipstick. The spring 48 tends to retain the casing sleeves in the operative disposition thereof illustrated in Figs. 1 and 2 by urging the collar 32 into abutment with the shoulder or detent 44. The outer bulge 40 on the outer cartridge sleeve serves to frictionally engage the casing cover 18 to retain the latter in releasable frictional engagement on the casing.

Pursuant to an important aspect of the present invention, the lipstick cartridge can be ejected positively from the casing without the necessity of first releasing the refill from the casing and then pulling it out by hand from the casing. It will be apparent from Fig. 2 that the lipstick cartridge is retained linearly within the casing due to the engagement of bulge 34 with the outer cartridge sleeve and the engagement of the friction sleeve 46 with the footpiece 56 of the inner cartridge sleeve.

Upon telescoping the inner and outer sleeves of the casing, as shown in Fig. 3, the footpiece 56 of the refill cartridge is positively projected from the casing due to the force exerted by the inner end 30 of the inner casing sleeve against the footpiece to project and expose the latter, as indicated by the arrows 68. Thereupon, the cartridge may be removed from the casing, as will be readily apparent, and as shown by broken line in Fig. 3. When the cartridge is removed, the casing parts remain in the relative positions thereof shown in Fig. 3, since the compressed spring 48 cannot overcome the friction between the casing parts. However, when a new cartridge is inserted into the casing, through the lower end 36a thereof, the casing sleeves are restored to the operative condition thereof, shown in Figs. 1 and 2, the compressed spring 48 expanding to facilitate the restoration of the sleeve positions which are properly disposed by the engagement of the collar 32 with the shoulder 44. The flange 28 serves as a positioning detent to properly locate the cartridge within the casing, as will be apparent from Fig. 2, due to the engagement of the outer end of the outer cartridge sleeve with the flange.

Referring now to Figs. 4 and 5 in detail, there is shown another embodiment of the invention. It will be understood that in the present embodiment, the refill cartridge is the same as that previously described. The casing 16A is constituted by the telescopically related inner sleeve 70 and outer sleeve 72. The inner sleeve has an outer open end defined by an inwardly directed flange 74 and an inner open end defined by the circumferential collar 76. The outer sleeve 72 has a lower sleeve portion 78 of enlarged diameter and an upper sleeve portion 80 of reduced diameter. The lower open end 82 of the outer sleeve is provided with an inner friction ring or sleeve 84 suitably secured to the inner surface thereof. An inwardly directed shoulder 86 is defined between the upper and lower portions of the outer sleeve of the casing. A cover 18 can be mounted on the casing 16A by frictional engagement with the outer surface of the upper sleeve portion 80, the upper surface of the shoulder 86 serving

as a detent for the cover in the same manner as the shoulder 44 in Fig. 1.

With the refill cartridge in position within the casing 16A, the outer sleeve 60a of the cartridge is frictionally engaged with the inner surface of the inner casing sleeve 70 and the footpiece 56 provided on the inner cartridge sleeve is frictionally engaged with the friction ring 84.

Consequently, it will be readily apparent that relative rotation of the casing sleeves will result in relative rotation of the cartridge sleeves for projecting the lipstick from the casing or for withdrawing the latter into the casing.

In order to eject the cartridge from the casing in a positive manner, it is necessary only to telescope the sleeves of the casing. When this is done, the inner sleeve collar 76 will be moved into engagement with the opposing surface 56b of the footpiece 56a so as to eject the cartridge from the casing, in the same manner as previously described in connection with Fig. 3, whereupon the cartridge can be readily removed from the casing without soiling the fingers or clothing of the user. The casing parts remain in telescoped position in which the collar 76 abuts the friction ring 84, and when a new cartridge is inserted into the casing, the sleeves thereof are restored to the condition thereof illustrated in Fig. 4 with the collar 76 abutting the shoulder 86 and the cartridge abutting flange 74 to properly position the casing parts and the cartridge within the casing, as shown in Fig. 4. Sleeves 82, 84 and footpiece 56a of refill cartridge are of quadrangular shape as seen in Fig. 5.

Referring now to Fig. 6 in detail, there is shown an additional embodiment of the present invention. It will be noted that the present embodiment combines features of the embodiments shown in Figs. 1 and 4. The casing 16B of the present embodiment is provided with the telescopically related inner and outer casing sleeves 88 and 90, respectively. The inner casing sleeve 88 is similar in all respects to the inner casing sleeve 70 of Fig. 4 except that it is provided with an inner surface friction bulge 34, as in Fig. 1, for frictional engagement with the outer cartridge sleeve 60, as shown in Fig. 2. The outer casing sleeve 90 is similar in all respects to the outer casing sleeve of Fig. 1, being provided with an upper end friction bulge 40 for frictional engagement with the cover 18, and an inner surface friction ring 46 for engagement with the cartridge footpiece 56. Consequently, it will be apparent that relative rotation of the casing sleeves will effect the movement of the lipstick 14 as previously described.

In order to effect the positive ejection of the cartridge from the casing, the casing sleeves are telescoped, whereupon the inner sleeve collar 76 will engage the opposing surface rim 56c of the footpiece 56, as previously described in connection with Fig. 4 to project the footpiece 56 from the casing for removal of the cartridge therefrom. The casing sleeves are restored to their operative position, as shown in Fig. 6, upon reinsertion of a new cartridge in the casing, as described in connection with Fig. 4.

Referring now to Figs. 7 and 8, there is shown a further embodiment of the present invention. Pursuant to the present embodiment, provision is made for a casing comprising the telescopically related inner and outer sleeves 92 and 94, respectively. Sleeve 92 terminates in an outer open end defined by the inwardly directed flange 28 and an inner open end defined by the outwardly directed flange 96. The outer sleeve 94 has a lower sleeve portion 98 of enlarged diameter which terminates in an open end defined by the inwardly directed flange 100 and an upper sleeve portion 102 of reduced diameter which terminates in an upper end opening defined by the inwardly directed flange 104. A compression spring 106 is mounted on the inner sleeve 92, being seated between the flange 96 thereof and the flange 104

of the outer sleeve. The compression spring 106, due to its inherent force, biases the inner sleeve 92 downwardly relative to the outer sleeve 94. The two sleeves are held in their spread apart position, as shown in Fig. 8, upon the insertion of the refill cartridge 12 which only frictionally engages the outer sleeve 94 by the engagement of a rim 110 of footpiece 56 of the cartridge with the inwardly directed flange or rim 100 of the outer sleeve.

Casing 16C having inner and outer sleeves 92, 94 may be made from any metal or material suitable for large scale production; spring 106 being completely encased between said sleeves 92, 94.

Sleeve 92 is properly disposed relative to sleeve 94, upon insertion of the cartridge, by the engagement of flange 96 with the shoulder 108 defined in the outer sleeve between the two portions thereof. It will be understood that the force of the stressed or loaded spring 106, in the condition thereof shown in Fig. 8, is insufficient to move the inner sleeve 92 downwardly relative to the outer sleeve 94 due to sufficiently strong frictional engagement of the cartridge rim 110 with the outer sleeve rim 100, the inner sleeve 92 only slightly and guidingly embracing the outer sleeve 60 of the cartridge 12, as shown in Fig. 7.

It will be apparent that when the outer casing sleeve 94 is rotated relative to the inner casing sleeve 92, the cartridge footpiece 56, which is integral with the inner cartridge sleeve, as previously described, will be rotated relative to the outer cartridge sleeve, which is frictionally engaged with the inner casing sleeve, to project or withdraw the lipstick 14, as previously described.

In order to effect the ejection of the cartridge from the casing, the casing sleeves are telescoped by the operator or user from the positions thereof shown in Figs. 7 and 8.

Such movement of the sleeves is limited by the engagement of the inner sleeve flange 96 with the outer sleeve rim 100, as shown in broken line in Fig. 8, and is facilitated by the expansion of the stressed spring 106. Such telescopic movement releases the frictional engagement of the footpiece rim 110 with the outer sleeve rim 100 so that the cartridge is no longer frictionally engaged with the outer sleeve 94. With the release of such frictional engagement, the force of the stressed spring 106 is sufficient to move the inner casing sleeve downwardly, as shown by the arrow 112, such movement being limited by the engagement of the inner sleeve flange 96 with the rim 100 of the outer sleeve. Such downward movement of the inner sleeve results in the complete ejection or expulsion of the cartridge from the casing, as shown by arrow 114. It will be noted from Fig. 7, that the inner sleeve flange 96 bears against an upper rim 116 provided on the footpiece 56 so that release of the frictional engagement 100-110 applies the force of spring 106 through flange 96 to the footpiece 56 to expel the cartridge from the casing. Consequently, it will be apparent that the cartridge is completely expelled from the casing so that it is not necessary to grip the footpiece 56 to remove the cartridge.

The two sleeves remain in their telescoped position, with the spring 106 expanded as shown in broken lines in Fig. 8, until a new cartridge is inserted to restore the sleeves to the condition thereof shown in Fig. 7 and to stress the spring, as shown in said latter figure.

From the foregoing, it will be apparent that in each of the embodiments of the present invention, the telescoping of the casing sleeves results in the positive projection of the footpiece of the cartridge from the casing without the necessity of fingering the cartridge whereby to prevent the soiling of the operators' or users' fingers, purse or clothing by the lipstick.

Various changes and modifications may be made without departing from the spirit and scope of the present

invention and it is intended that such obvious changes and modifications be embraced by the annexed claims.

Having thus described the invention, what is claimed as new and desired to be secured by Letters Patent, is:

- 5 1. A casing for a refill housing of the type having an outer housing sleeve within which there is rotatably disposed an inner housing sleeve for projecting an article from and for withdrawing said article into said outer housing sleeve by relative rotation of said sleeves, said
- 10 casing comprising a pair of telescopically related tubular members, means to limit the telescopic movement of said members in a first direction of increased telescopic relation, means to limit the telescopic movement of said members in a second direction of decreased telescopic
- 15 relation, the inner tubular member having means to frictionally engage the outer housing sleeve and the outer tubular member having means to frictionally engage the inner housing sleeve, whereby relative rotation of said tubular members effects relative rotation of the housing sleeves and telescoping of said tubular members in said first direction positively ejects the housing from the casing, said limit means comprising axially spaced detent means provided on the outer tubular member and a complementary portion of said inner tubular member movable
- 20 between said spaced detent means, said friction engaging means comprising an inner surface friction portion on each of said tubular members, and one of said detent means being the friction engaging means of said outer tubular member.
- 25 30 2. A casing for a refill housing of the type having an outer housing sleeve within which there is rotatably disposed an inner housing sleeve for projecting an article from and for withdrawing said article into said outer housing sleeve by relative rotation of said sleeves, said casing comprising a pair of telescopically related tubular members, the inner tubular member having means to frictionally engage the outer housing sleeve and the outer tubular member having means to frictionally engage the inner housing sleeve, whereby relative rotation of said tubular
- 35 members effects relative rotation of the housing sleeves and telescoping of said tubular members positively ejects the housing from said casing, said friction engaging means comprising an inner surface friction portion on each of said tubular members, the friction engaging portion of the outer tubular member being constituted by a friction ring, and the friction engaging portion of the inner tubular member being constituted by a friction bulge, means to limit the telescopic movement of said tubular members in both directions, said limit means comprising axially
- 40 spaced detent means provided on the outer tubular member and a complementary portion of said inner tubular member movable between said spaced detent means, and one of said detent means being the friction engaging means of said outer tubular member.
- 45 55 3. A casing for a refill housing of the type having an outer housing sleeve within which there is rotatably disposed an inner housing sleeve for projecting an article from and for withdrawing said article into said outer housing sleeve by relative rotation of said sleeves, said casing comprising a pair of telescopically related tubular members, the inner tubular member having means to frictionally engage the outer housing sleeve and the outer tubular member having means to frictionally engage the inner housing sleeve, whereby relative rotation of said tubular
- 50 members effects relative rotation of the housing sleeves and telescoping of said tubular members positively ejects the housing from said casing, said friction engaging means comprising an inner surface friction portion on each of said tubular members, the friction engaging portion of the outer tubular member being constituted by a friction ring, and the friction engaging portion of the inner tubular member being constituted by a friction bulge, means to limit the telescopic movement of said tubular members in both directions, said limit means comprising axially spaced detent means provided on the outer tubular member and a complementary portion of said inner tubular member movable between said spaced detent means, and one of said detent means being the friction engaging means of said outer tubular member.
- 60 65 4. A casing for a refill housing of the type having an outer housing sleeve within which there is rotatably disposed an inner housing sleeve for projecting an article from and for withdrawing said article into said outer housing sleeve by relative rotation of said sleeves, said casing comprising a pair of telescopically related tubular members, the inner tubular member having means to frictionally engage the outer housing sleeve and the outer tubular member having means to frictionally engage the inner housing sleeve, whereby relative rotation of said tubular
- 70 members effects relative rotation of the housing sleeves and telescoping of said tubular members positively ejects the housing from said casing, said friction engaging means comprising an inner surface friction portion on each of said tubular members, the friction engaging portion of the outer tubular member being constituted by a friction ring, and the friction engaging portion of the inner tubular member being constituted by a friction bulge, means to limit the telescopic movement of said tubular members in both directions, said limit means comprising axially spaced detent means provided on the outer

tubular members and a complementary portion of said inner tubular member movable between said spaced detent means, and resilient means interengaging said tubular members, said resilient means being disposed between the lower one of said detent means and said complementary portion, whereby said resilient means is stressed by telescopic movement of said tubular members to eject said housing.

4. A casing for a refill housing of the type having an outer housing sleeve within which there is rotatably disposed an inner housing sleeve for projecting an article from and for withdrawing said article into said outer housing sleeve by relative rotation of said sleeves, said casing comprising a pair of telescopically related tubular members, the inner tubular member having means to frictionally engage the outer housing sleeve and the outer tubular member having means to frictionally engage the inner housing sleeve, whereby relative rotation of said tubular members effects relative rotation of the housing sleeves and telescoping of said tubular members positively ejects the housing from said casing, said friction engaging means

comprising an inner friction surface portion on each of said tubular members, the friction engaging portion of the outer tubular member being constituted by a friction ring, and the friction engaging portion of the inner tubular member being constituted by a friction bulge, means to limit the telescopic movement of said tubular members in both directions, said limit means comprising axially spaced detent means provided on the outer tubular member and a complementary portion of said inner tubular member movable between said spaced detent means, and resilient means interengaging said tubular members, said resilient means being disposed between the upper one of said detent means and said complementary portion, whereby said resilient means is relaxed by telescopic movement of said tubular members to eject said housing.
